UNITED STATES PATENT OFFICE

171,904

ILLUMINABLE READING GLASS

Michael Macaluso, Jr., Rochester, N. Y., assignor
to Bausch & Lomb Optical Company, Rochester, N. Y., a corporation of New York

Application January 19, 1953, Serial No. 23,180

Term of patent 14 years

(Cl. D57—7)

To all whom it may concern:

Be it known that I, Michael Macaluso, Jr., a citizen of the United States and a resident of Rochester, county of Monroe and State of New York, have invented a new, original, and ornamental Design for an Illuminable Reading Glass, of which the following is a specification, reference being had to the accompanying drawing, forming a part hereof.

Fig. 1 is a front elevational view of an illuminable reading glass, showing my new design.

Fig. 2 is an elevational view of the right side thereof as viewed in Fig. 1.

Fig. 3 is a rear elevational view thereof.

Fig. 4 is an elevational view of the left side thereof as viewed in Fig. 1.

I claim:

The ornamental design for an illuminable reading glass, substantially as shown.
